UNITED STATES PATENT OFFICE.

WILLIAM M. ORR, OF ORRVILLE, OHIO, ASSIGNOR TO CRYSTAL BURIAL CASE COMPANY, OF SAME PLACE.

COFFIN.

SPECIFICATION forming part of Letters Patent No. 235,376, dated December 14, 1880.

Application filed October 30, 1879.

To all whom it may concern:

Be it known that I, WILLIAM M. ORR, of Orrville, in the county of Wayne and State of Ohio, have invented certain new and useful Improvements in Coffins, Caskets, or Burial-Cases; and I do hereby declare the following to be a full, clear, and exact description of the invention, such as will enable others skilled in the art to which it pertains to make and use it, reference being had to the accompanying drawings, which form part of this specification.

My invention relates to caskets or coffins; and it consists, broadly, in forming the bottom of said coffin or casket with a counter-sunk portion, whereby a flanged or shouldered portion of the bottom is raised so as not to touch the base upon which the coffin may rest, by the provision of which flanged or raised portion handles may be attached that shall lift the weight of the casket from its bottom instead of its sides, and whereby also said handles shall be raised above the base or floor upon which the coffin rests.

In the drawings, Figure 1 represents an end view of a coffin constructed according to my invention; Fig. 2, a transverse vertical section of the same.

In the said drawings, A is the body; B, its lid or cover; C, the handles; D, the sunken bottom portion, and E the flanged or raised portion of the bottom.

Instead of making the bottom flat its main portion D is sunken, leaving thereby a raised or flanged portion, E, of the bottom entirely surrounding or laterally bounding the sunken portion D. To the raised or flanged portion E handles C may be attached in any suitable manner. What these handles shall be or how they shall be attached, whether adjustably, removably, or otherwise, constitutes no specific part of my invention, as any handles of any description may be used, constructed to be attached to or proceed from the raised bottom portion, E, and to project upward therefrom, substantially as shown.

The handles may be made integral with the

raised bottom portion, E, or may be made independently thereof and connected therewith in any desired manner.

This construction enables a coffin to be lifted squarely from its bottom instead of from its sides; and on account of this construction much lighter material can be employed in the construction of caskets, and an evident safety against breakage of the coffin from its own weight and the weight of its contents, caused by lifting it from handles attached at its sides, is effectually obviated.

By the provision of the raised portion E the handles are also lifted above any floor or foundation upon which the coffin rests, and are therefore not liable to scratch or damage the floor of a hearse, table, or whatever upon which the coffin may be laid.

I do not limit myself to the employment of this bottom in any specific construction of coffins or caskets, whether wooden, metallic, vitreous, or otherwise, as it is equally well adapted to all coffins made from any material whatever.

What I claim is—

1. A coffin, casket, or burial-case provided with shoulders between the bottom and sides of the coffin, and handles connected with said shoulders, substantially as set forth.

2. The combination, with a coffin, casket, or burial-case constructed with square shoulders C, integral with the bottom of the coffin and beneath the lower edges of the sides thereof, of handle-irons suitably formed to be secured to the horizontal portion of shoulder C and project upwardly any desired distance for the attachment of handles to their upper ends, substantially as set forth.

In testimony whereof I have signed my name to this specification in the presence of two subscribing witnesses.

WILLIAM M. ORR.
